DISPENSING APPARATUS FOR LUBRICANT
AND THE LIKE

Marvin S. Young, Scarsdale, N. Y., and Raymond B. Lewthwaite, Hasbrouck Heights, N. J., assignors to The Merlin Corporation, New York, N. Y., a corporation of Delaware

Application August 23, 1938, Serial No. 226,208

25 Claims. (Cl. 221—47.1)

This invention relates to a new and improved apparatus and practices for dispensing liquid and particularly for dispensing liquid lubricants in the operation of service stations for motor vehicles. The invention more particularly relates to improvements in apparatus for preventing fraudulent substitution of grades or brands in the dispensing of lubricant, and it provides new arrangements and constructions of supply containers and cooperating liquid inlet systems for liquid dispensers which may be used to considerate advantage in the marketing and dispensing of lubricating oil.

In our co-pending application, Serial No. 214,448, filed June 18, 1938, we have disclosed a new type of portable liquid dispenser, for use in dispensing lubricating oil and the like, comprising novel means for establishing communication and flow of liquids from normally separate and independent supply containers into small portable liquid dispensers, together with new arrangements and combinations of means in such dispensers for pumping and metering lubricant from attached portable containers and delivering the lubricant directly to points of dispensation in full view of purchasers. According to certain embodiments of our prior invention, a sealed supply container is placed and held in fluid-tight engagement with parts adjacent a feed or control compartment of the dispenser by simple movement of the container when fixing it to the dispenser. Oil is pumped directly from the container through the portable dispenser and into a waiting vehicle, the amount of oil discharged being metered accurately during its passage to the point of use. When the attached supply container has been emptied the dispenser automatically becomes inoperative, and remains inoperative and substantially full of oil until the emptied container has been removed and another supply container has been attached. The invention disclosed in said prior application provides numerous other new features and advantages in the dispensation of lubricants, all as more fully set forth in the application itself. In the instant invention, as in said prior application, dispensing devices are provided for use in full view of purchasers of lubricant, and liquid may be fed from attached supply containers into the dispensers and metered accurately as it passes from an attached container through the dispenser to the point of dispensation, such as the crankcase of an automobile.

This invention deals with new and useful improvements that are particularly valuable for use

with portable dispenser systems of the types disclosed in our prior application. It has as its main purpose the provision of a system for controlling the inflow of liquids, for example, lubricating oils, from normally separate and independent supply containers into cooperating portable dispensing units whereby continuous protection against fraudulent substitution of unauthorized grades or brands of lubricant can be had from the initial manufacturing source to the final consumer.

Another object of this invention is to prevent unauthorized supplying of liquid to portable liquid dispensers, particularly of the types disclosed in our prior application identified above.

Still another object of the instant invention is to provide liquid dispensers, for dispensing and metering liquid from portable supply containers, which are equipped with inlet systems preventing the association of any supply containers in co-operation with the dispensers except such containers as are specially constructed therefor, said inlet systems being responsive only to actuation by such containers to place the containers in co-operation with the dispensers.

Other objects of the instant invention are to provide improved means for placing and clamping supply containers in sealed communication with liquid dispensers, and to provide means for locking the clamping means in inoperative position when a container is removed from the dispenser, thereby preventing unauthorized containers from being placed in cooperation therewith.

Further objects of the instant invention are to provide new and useful containers for lubricating oil and the like which embody novel means for improving the drainage of liquid therefrom, and to provide such containers which are constructed specially to cooperate in keyed relationship with keyed dispensing systems to restrict the containers to use with particular dispensing systems.

These and other objects and features of our invention will be made apparent by the ensuing detailed description of an illustrative embodiment thereof when considered in conjunction with the accompanying drawings.

In the drawings,

Figure 1 is a perspective view of a typical dispenser such as provided by our invention, with sealed supply containers in cooperating position thereon and with the assembly in condition for delivery of lubricating oil into the crank case of an automobile.

Figure 2 is a vertical cross-sectional view along line 2—2 of Figure 1, showing one of the containers in cooperation with the dispenser and showing details of construction of the container and dispenser inlet system, according to a preferred embodiment of the present invention.

Figure 3 is a horizontal section through the container, along line 3—3 of Figure 2, showing a particular construction of the container end wall, or bottom, and the arrangement thereof in cooperation with the dispenser inlet system.

Figure 4 is a fragmentary plan view, partly in section, showing a fragment of the container bottom and parts of the dispenser inlet system.

Figure 5 is a vertical cross-sectional view along the line 5—5 of Figure 4, showing details of a can bottom in sealed communication with the inlet system.

Figure 6 is a horizontal cross-section along the line 6—6 of Figure 5.

Figure 7 is a detailed vertical cross-section along the line 7—7 of Figure 4, showing locking means for the inlet system, with the latter in its unlocked position and with a container in communication therewith.

Figure 8 is a fragmentary plan view of parts of the inlet system in the inoperative position which they assume when a container is removed therefrom.

Figure 9 is a vertical cross-section along line 9—9 of Figure 8.

Figure 10 is a vertical cross-section along line 10—10 of Figure 8, showing the locking means in its locked position, before a properly keyed container has been placed in cooperation with the inlet system.

Figure 11 is an elevation, partly in section, showing details of the piercing and cutting element of the inlet system.

Figure 12 is a perspective view of a novel sealed container.

According to our prior invention, instead of dispensing lubricating oil from individual containers, one for dispensing each unit quantity of oil, the oil may be carried to locations close to waiting vehicles in portable supply containers, which may be sealed cans of standard size that hold enough oil for several dispensations and that have been packed, sealed, and branded before delivery for retail sale, and at such locations the containers may be placed in cooperating communication with properly constructed portable dispensers by which the oil is liberated, fed directly from the supply containers to points of dispensation, and metered accurately during passage to such points.

According to the present invention, all of the valuable objects and features of our prior application may be realized, and in addition both the user and the producer of the oil are further protected against fraudulent substitution of unauthorized grades or brands of oil by the use of novel supply containers and novel dispensers having special inlet systems for establishing communication and flow of liquid between properly keyed containers and the dispensers.

By virtue of this protection against substitution, the attendant of a service station may be prevented from using a dispenser for dispensing any grade or brand of oil other than authorized for use in that dispenser, and thus the purchaser who orders a particular grade or brand is assured of receiving oil of the quality ordered. The producer or distributor of the oil may store it in branded containers of standard size which are

keyed according to a pre-determined plan so that they will cooperate only with authorized and properly keyed dispensers. In this way all normal methods of fraudulent substitution may be prevented from the moment the oil is packed in sealed containers until it is actually delivered to the purchaser.

Another important feature of the present invention is that it results in valuable savings of oil in comparison with existing practices. As in the case of the improvements disclosed in our prior application, the dispensers may be constructed to dispense alternately from two different attached supply containers, so that after one container has been emptied it may conveniently be left in place to drain thoroughly before another full container is substituted. In addition, as in the prior application, means may be provided for shaping the bottoms of the containers while in place so as to promote more thorough drainage. A further feature of the present application resides in the provision of specially constructed supply containers which enable substantially complete drainage of liquid therefrom and avoid the retention of liquid by walls of the container, such as occurs in the use of containers of usual construction. From three to six ounces of lubricating oil are retained in each can when oil is dispensed from individual quart cans according to common practice. This oil is either discarded with the "emptied" cans, or a substantial amount of it may be recovered by the service station operator through special drainage of the cans. Our improved dispensers and containers minimize this loss or diversion of oil from intended channels of distribution, thus ensuring that purchasers receive the full amounts for which they have bargained and that all of the oil be marketed in an authorized manner.

The portable dispenser shown in Figure 1 of the accompanying drawings is generally similar to an embodiment illustrated in our prior application. The present drawings, however, are intended principally to illustrate new combinations and constructions by which we attain the special objects and features mentioned hereinabove. As described more particularly in said prior application, the illustrated embodiment comprises a portable carriage 10 having means such as legs 12 for supporting the same in upright position, structural members 14 for mounting parts of the dispensing mechanism, and a casing 15 with top and side walls. A feed compartment 16 is located adjacent one end of the carriage, this compartment having an opening 18 in its upper portion communicating with a port of the liquid inlet system, through which liquid flows from an attached portable supply container A, and an opening 20 in its lower portion communicating with a connected branch conduit 22. A similar feed compartment and inlet system may be located on another part of the carriage, for cooperation with an attached supply container B, and both compartments serve to receive liquid for delivery, when the dispenser is operated, through feed lines including a vertical portion 26, a delivery hose 28 and a nozzle 32. The liquid is withdrawn from a supply container and fed from an underlying feed compartment by means of an upright pump 41 having a plunger handle 46. For convenience, a handle 48 may be mounted on the pump barrel to facilitate lifting and movement of the entire dispenser assembly. The liquid advanced by the pump 40 passes through a meter 50, the dial of which preferably is ex-

posed above the top wall of casing 15. A compartment or "visi-gauge" 52, having transparent walls, may be provided on portion 26 to permit full vision of the stream of liquid entering hose 28 for delivery, and a bracket 54 also may be carried by portion 26 to support the hose when not in use.

In addition, the dispenser may be equipped with means for constantly keeping its feed lines 10 full of liquid and for preventing entrance of air into the feed lines after a communicating supply container has been emptied. Thus the nozzle comprises a valve 34 which permits liquid to be discharged under pressure but prevents the entrance of air into the hose; the conduit 22 has a spring-pressed valve 60 which normally rests against a seat 62 to prevent the passage of liquid out of the feed lines in the direction of compartment 16; and each feed compartment is provided 15 with means for blocking the flow of liquid into the feed lines, in response to the level of liquid in the compartment, after an attached supply container has been emptied; such means including a valve 70 connected with a float 74 by links 20 fulcrumed at 72 and adapted to move against a valve seat 76 when the float is lowered.

The nozzle also comprises an internal valve, controlled by a valve handle 38, for preventing delivery of liquid except when the valve is open. 30 Further, the inlet system for the dispenser, when adapted for establishing communication and flow of liquid thereto from frangible supply containers, such as sealed tin cans, may embody certain features similar to those illustrated 35 in our prior application. Each feed compartment has a throat 100 communicating with the inlet system at one end and with opening 18 at the other end. A piercing device 102, including one or more piercing and cutting elements 104 and a 40 tubular shank 106, projects above the inlet port and communicates with throat 100. Openings 108 are provided in shank 106 to facilitate flow of liquid from an attached supply container. A sealing member such as a resilient collar 110 is 45 arranged around shank 106 for sealing the end, or bottom, wall of a container to avoid escape of liquid, and means are provided for holding the bottom wall in contact with the sealing member when the container is in dispensing position, as 50 described below. A drip plate 112, yieldable under pressure, surrounds the piercing device 102, underlying a large part of the container bottom wall. The drip plate must be pushed downwardly 55 against the compression of a spring 114 before the pierced container wall can be placed and held in sealed relation to collar 110, so that the spring raises the body of the container after its bottom wall has been fixed in place and thus inclines the bottom wall toward openings 108 to improve the 60 drainage of liquid from the container. Venting means are provided for admitting pressure into the supply container as required for the pumping of liquid therefrom, in the form of a tube 116 which opens at one end into a container embracing 65 the piercing device 102, passes downwardly through throat 100 and opening 18, and communicates with the atmosphere at its other end through a spring-pressed valve 118. Valve 118 admits air under atmospheric pressure to tube 70 116 when the pressure in the supply container is lower than atmospheric.

The foregoing features of arrangement, construction and operation are mentioned merely as representative of certain types of dispensers with 75 which the present improvements may be used to

advantage. The improvements disclosed and claimed herein are useful with other combinations and constructions without restriction to features of the illustrated embodiment.

According to the present invention, new combinations of dispenser inlet systems and supply containers are provided in which each inlet system is keyed to fit and cooperate with specially keyed containers, and in which the keying means prevents improperly keyed containers from being placed and held in cooperating relation to the system. Further, each inlet system comprises movable means for clamping the containers in cooperating and sealed relation thereto, and the clamping means remain in an inoperative position when a container is absent from the combination but are movable to an operative position in response to movement of a properly keyed container.

In the illustrated embodiment of these improvements, the inlet system leading to each feed compartment of the dispenser is adapted for cooperation with sealed and frangible supply containers of a standard size, such as sealed tin cans holding five quarts of lubricating oil. A guide 120 is provided around piercing device 102 in order to center such a can accurately and to hold it in centered relation when pushed downwardly onto the piercing device. Thus a can of greater diameter than the standard cannot be placed in the guide, while a can of less diameter than the standard can hardly be centered properly.

Within the guide 120 and in the path of a can moving therein the inlet system is provided with keying elements which further prevent the placement of containers in cooperation with the system, regardless of their diameter, except such containers as are constructed to coact with the keying elements. For example, a series of lugs 122 project upwardly from a platform 124 adjacent which the can bottom 200 must rest when located in cooperating and sealed relation to the system. The tops of these lugs extend above the sealing member 110, and they prevent any ordinary can from being moved into contact therewith by engaging and limiting downward movement of the can. Should an improperly keyed container of suitable diameter be placed in guide 120 and pushed onto the piercing device 102, the container would be ruptured and its contents 30 freed, but lugs 122 would prevent sealing of the container bottom and the liquid would be free to escape onto the drip plate 112.

For cooperation with this system we provide containers which are keyed to fit the keying elements of the inlet system and thus to be movable to a position adjacent platform 124 in contact with sealing member 110. For example, the bottom wall 200 of each container includes integral cups forming recesses 202 which correspond in form and arrangement to the form and arrangement of lugs 122, and which fit over the lugs when the container is centered over the piercing device. (See Figures 2, 3 and 12.) While six lugs 122 and six recesses 202, of approximately equal size and equal spacing, are shown in the drawings, it will be understood that the form, location and arrangement of the keying elements can be given almost infinite variation, so that each producer of lubricant may use a particular keying system for each grade or brand of his products.

It will be observed that a properly keyed container may be pushed downwardly onto the inlet system, as thus far described, and then turned, if necessary, to fit recesses 202 over lugs 122.

The can, however, remains unclamped to the system, and escape of liquid or admission of air between its bottom wall and sealing member 110 is still likely to occur. We therefore provide 5 mechanism for clamping the can bottom in co-operating and sealed relation to the system, in response to movement of the container, for example, as follows: The platform 124 comprises a movable ring 130 which may be rotated within 10 a sleeve 132. A plurality of clamps 134, each having a cam face 136, are arranged to move from an inoperative position inside the tubular portion 106 of piercing device 102 to an operative position extending radially through the openings 108 15 and overlying the sealing member 110. Connecting means are provided between ring 130 and clamps 134 so that the clamps move to and from their operative position in response to movement of the ring. For example, each clamp may be 20 formed as one leg of a U-shaped member 138, the other leg 140 of which is slidably held in a radial groove 142 in ring 130. Ring 130, members 138 and device 102 turn together about the axis of the piercing device when the ring is actuated 25 by the container A, and all turn relative to a stationary plate 144. Each leg 140 has a pin 146 united thereto and extending into an arcuate slot 148 in plate 144. When ring 130 is turned in a counterclockwise direction, as viewed in Figures 30 4, 6 and 8, pins 146 are guided toward the axis of the piercing device by slots 148, and the clamps 134 are moved radially to inoperative position (Figure 9). When ring 130 is moved clockwise, pins 146 are guided away from the axis and 35 clamps 134 are moved radially to operative position overlying sealing member 110 (Figure 5).

From the foregoing it will be apparent that when a properly keyed container is pushed downwardly over the piercing device 102, turned, if 40 necessary, to fit its keying elements with the keying elements of the inlet system, and then turned in a clockwise direction, the interengagement of the keying elements causes ring 130, sealing member 110, piercing device 102, and members 138 to 45 turn with the can, and clamps 134 are thereupon moved outwardly so that their cam faces 136 engage over the cut edge of the can bottom 200 and force the bottom into sealing engagement with member 110. Compare Figure 9 and Figure 5. 50 After such clamping of the can into cooperation with the inlet system, the can cannot be removed properly except by turning it in a counterclockwise direction to withdraw clamps 134.

In conjunction with the combinations and arrangements above described, we preferably provide locking means for locking the clamping means in inoperative position except upon actuation by properly keyed supply containers. In the illustrative embodiment, as shown in Figures 7 55 and 10, a locking plunger 150 is located in a well 152 in plate 144 and a spring 154 tends to press the plunger upwardly beyond the surface of the plate. A cooperating plunger 156 is mounted for vertical movement in a well 158 in ring 130, 60 plunger 156 having a part 160 extending through and above the surface of ring 130. When ring 130 is turned to bring clamps 134 into inoperative position and a cooperating container is absent from the inlet system, well 152 registers with 65 well 158 and plunger 150 is pressed into the latter by spring 154, thus locking ring 130 and preventing movement of the same relative to plate 144. When a properly keyed contained is placed 70 on the inlet system, however, the bottom wall 200 of the container presses part 160 and plungers 75

150 and 156 downwardly against spring 154 and frees the ring 130 for turning movement, as shown in Figure 7 of the drawings. On the other hand, when an unkeyed or improperly keyed container is placed on the inlet system, even though pressed down on lugs 122 hard enough to engage the lugs, the bottom of the container is held away from part 160 by the lugs and the ring remains locked by plunger 150 and will not turn. One or more of these locking mechanisms may be employed as 10 described. In the illustrated embodiment two are provided, the second including a part 160¹ diametrically opposed to part 160 of the mechanism described above. Each of these parts is advantageously located near a keying element so that 15 containers which are not specially constructed for the particular system will be prevented from releasing the locking mechanism under all circumstances.

When using sealed tin cans for the supply containers we preferably employ means for facilitating drainage of liquid from the cans, such as the spring-pressed drip plate 112, so that when a can bottom is held by the clamps 134 the remainder of the can is pressed away from the clamps and 20 the bottom thus is shaped or inclined toward openings 108. The usual tin cans, however, are difficult to drain completely notwithstanding the use of special drainage facilities with the inlet 25 system.

According to a further feature of our invention, we provide new supply containers having end or bottom walls constructed in a novel manner to retain the requisite strength when made of light weight metal stock and to drain thoroughly when used with our improved liquid dispensers. In 30 place of bottoms with annular reenforcing ribs such as employed in usual sheet metal can constructions, which tend to hold the oil and prevent thorough drainage, our improved frangible 35 containers have bottom walls formed with an annular series of ribs and passages 204 and 206, respectively, extending radially from adjacent the periphery of the container toward the center of the bottom wall. (See Figures 3 and 12.) The 40 ribs 204 preferably terminate short of the center to bound a flat central wall section 208 connected with passages 206 without intervening protuberances or projections which would impede 45 the flow of liquid toward the center of the bottom 50 wall. The central section is thus kept large enough to span the piercing device 102 of our dispensers and to provide space for keying elements 202, if such are to be used, while adequate 55 strength is imparted to the wall by ribs 204.

Still another feature of the illustrated embodiment of this invention resides in the novel construction of the venting tube 116 and in the novel arrangement thereof in combination with other elements of the keyed inlet system. In the form 60 shown in Figure 2 of the drawings, the tube comprises telescoping sections 116a and 116b, the former normally extending to a point adjacent the piercing points 104 under the influence of a compression spring 119. When a container having a frangible bottom wall is pressed downwardly toward a position for cooperation with the inlet system, the central portion of the container wall forces tube section 116a downwardly against spring 119 until such portion is cut out of the 65 wall by the piercing and cutting device 102. Thereupon, spring 119 restores section 116a to normal position and displaces the cut-out wall portion. When the container is properly positioned for dispensing, the open end of tube sec- 70 75 80 85 90 95 100

tion 116a extends a considerable distance above the zone where liquid flows from the container, and an effective venting action is obtained which facilitates the flow of viscous liquids such as heavy lubricating oils.

While the improvements herein disclosed are especially valuable for use with sealed frangible supply containers, it should be understood that the utility of the invention is not restricted to such practice but extends also to the use of keyed portable supply containers of any desired construction which may be placed in cooperating relation to the inlet system of a dispenser and easily removed therefrom after its content of liquid has been metered and dispensed by the operation of the device. Such optional containers may have preformed valved openings, making the piercing and cutting means unnecessary. It will also be apparent that the benefits of the present invention may be realized by the use of many other structural embodiments without limitation to the details of construction and arrangements that are used in the illustrated embodiment. We therefore desire that the invention be accorded a scope fully commensurate with its contribution to the art as determined by a fair construction of the claims.

We claim:

1. In combination, a liquid dispenser having a liquid inlet system for establishing communication between the dispenser and a cooperating supply container, said system comprising a fixed guide, keying means within the guide, preventing placement of an improperly keyed container in cooperation with the system, a container fitting within said guide and having keying means thereon which interengage with the aforesaid keying means, and means separate from said keying means for establishing flow of liquid from the container when the container is placed within said guide.

2. In combination, a liquid dispenser having a liquid inlet system for establishing communication between the dispenser and a cooperating supply container, said system comprising an inlet port, a fixed guide surrounding said port and open at one end to permit the placement of a container therein axially with respect to said port, keying means within said guide above and spaced laterally from said port for preventing the placement of an improperly keyed container in cooperation with the system, and means operative when a container having keying means complementary to the aforesaid keying means is moved within said guide for opening and fixing the container to deliver liquid therefrom only into said port.

3. A liquid dispenser having a keyed liquid inlet system for establishing communication between the dispenser and keyed frangible supply containers, said system comprising an inlet port, piercing and cutting means projecting above said port for piercing and opening a sealed wall of a frangible container when moved toward the port, keying means, clamping means movable relative to said port, and means responsive to rotation of a container having complementary keying means interengaged with said keying means for moving said clamping means to an operative position holding the container in position to deliver its contents into said port.

4. A liquid dispenser having a liquid inlet system for establishing communication between the dispenser and cooperating supply containers, said system comprising an inlet port, container seal-

ing means surrounding said port, keying means above said sealing means for preventing the placement of all but properly keyed containers in sealing contact therewith, means for opening a container to free its contents when moved toward said port, clamping means movable relative to said port for holding an opened and properly keyed container in contact with said sealing means, and means operable only after a properly keyed container has been interengaged with said keying means and placed in sealing position for actuating said clamping means.

5. In a liquid dispenser, a keyed inlet system including an inlet port, means for opening a wall of a supply container and freeing its contents as the container is moved axially toward said port, keying means adjacent said port for cooperating interengagement with an opened container only when the container has complementary keying means and has been moved toward and positioned adjacent to said port, and means responsive to movement of a properly keyed container that has been so positioned for clamping the container in a position ensuring delivery of its contents into said port.

6. In a liquid dispenser, a keyed inlet system including an inlet port, means for opening a wall of a supply container and freeing its contents as the container is moved axially toward said port, container sealing means surrounding said port, keying means adjacent said port for cooperating interengagement with an opened container only when the container has complementary keying means and has been moved toward and positioned adjacent to said port, and means responsive to movement of a properly keyed container that has been so positioned for clamping the opened wall of the container in sealed relation to said sealing means.

7. In a liquid dispenser, a keyed inlet system including an inlet port, means for opening a wall of a supply container when moved toward said port, keying means for cooperating interengagement with complementary keying means on a keyed supply container when such a container is positioned adjacent said port, clamping means movable relative to said port for clamping the container in such position and means responsive to turning movement of such a container about the axis of said port for actuating said clamping means.

8. In a liquid dispenser, an inlet system including an inlet port, container sealing means surrounding said port, a plurality of movable clamps for holding a supply container in sealing contact with said sealing means and in communication with said port, when the clamps are in operative position, a plurality of keying elements above said sealing means, and means responsive to movement of a container having keying elements interengaging with the aforesaid keying elements for moving said clamps to operative position.

9. In a liquid dispenser, an inlet system including an inlet port, container sealing means surrounding said port, a plurality of clamps movable from an inoperative position inside said sealing means to an operative position overlying the same, piercing and cutting means extending above said port for piercing and opening a wall of a frangible container when the container is moved toward the port, and means responsive to turning movement of a pierced container for moving said clamps to operative position and

- clamping the pierced wall of the container in engagement with said sealing means.
10. In a liquid dispenser, an inlet system including an inlet port, container sealing means surrounding said port, piercing and cutting means comprising at least one piercing point and a tubular shank extending above said port inside of the sealing means, a plurality of openings in said tubular shank adjacent said sealing means, a plurality of clamps movable from an inoperative position within said shank to an operative position extending through said openings and overlying said sealing means, and means responsive to turning movement of a pierced container in contact with said sealing means for moving said clamps to operative position and clamping the pierced wall thereof in engagement with the sealing means.
11. In a liquid dispenser, an inlet system including an inlet port, container sealing means surrounding said port, a fixed guide around said sealing means for guiding a container toward said port, piercing and cutting means extending above said port for piercing and opening a wall of a frangible container when moved toward the port, keying means within said guide and above said sealing means for preventing the placement of an improperly keyed container in cooperation with the system, movable clamping means for holding a properly keyed container in cooperation with said system, and means responsive to turning movement of a properly keyed and pierced container for moving said clamping means to operative and inoperative positions.
12. In a liquid dispenser, an inlet system for establishing cooperation between the dispenser and keyed supply containers, said system including clamping means movable from an inoperative position to an operative position engaging and holding a properly keyed container in cooperation with the system, keying means, means for locking said clamping means in inoperative position, said locking means being released only by interengaging a properly keyed container with said keying means, and means responsive to the turning of a container so engaged for moving said clamping means to operative position and holding the container in cooperation with the system.
13. An inlet system for liquid dispensers, said system comprising an inlet port, container piercing and cutting means adjacent said port, a resilient collar surrounding said port, a plurality of radially movable clamping cams, a rotatable annular ring having keying elements thereon adapted to interengage with a properly keyed frangible container, and means responsive to turning movement of a container interengaging with said keying elements for actuating said clamping cams and establishing sealed communication between the container and said inlet system.
14. An inlet system for liquid dispensers, said system comprising an inlet port, container piercing and cutting means adjacent said port, a resilient collar surrounding said port, a plurality of radially movable clamping cams, a rotatable annular ring having keying elements thereon adapted to interengage with a properly keyed frangible container, locking means for preventing rotation of said ring, means responsive to placement of a properly keyed container in interengagement with said keying elements for releasing said locking means, and means responsive to turning movement of a container so placed for actuating said clamping cams and establishing sealed communication between the container and said inlet system.
15. A liquid dispenser having a keyed liquid inlet system for establishing communication between the dispenser and keyed frangible supply containers, said system comprising an inlet port, piercing and cutting means projecting above said port for piercing and opening a sealed wall of a frangible container when moved toward the port, means yieldable under pressure for engaging and moving with the container when the container is pressed toward the port, keying means, movable clamping means adjacent said port, and means responsive to rotation of a container having complementary keying means interengaged with said keying means for moving said clamping means to an operative position holding the pierced wall of the container in cooperation with the system, the remainder of the container when its pierced wall is so held being pressed away from said clamping means by said yieldable means to incline said wall toward said port.
16. A supply container for liquid lubricant and the like having a generally flat frangible end wall, an annular series of ribs in said wall extending from adjacent the periphery toward the center of the wall and terminating short of the center to define an annular series of liquid drainage channels between said ribs which converge toward the center of said wall.
17. A supply container for liquid lubricant and the like having a generally flat frangible end wall and an annular series of radially extending ribs in said wall terminating short of the center thereof and bounding a substantially flat central wall section in substantially the same plane as radial channels between said ribs.
18. A supply container for liquid lubricant and the like having a frangible sheet-metal end wall and a plurality of keying elements formed integrally with said wall inside the margins thereof for cooperation with complementary keying elements of a keyed dispenser inlet system.
19. A supply container for liquid lubricant and the like having a frangible sheet-metal end wall and a plurality of keying elements die-pressed in said wall symmetrically about the center and inside the margins thereof for cooperation with complementary keying elements of a keyed dispenser inlet system.
20. A supply container for liquid lubricant and the like having a frangible end wall, an annular series of radially-extending ribs in said wall terminating short of the center thereof and bounding a substantially flat central wall section communicating with radial drainage channels between said ribs, and a plurality of keying elements formed integrally with said central wall section for cooperation with complementary keying elements of a keyed dispenser inlet system.
21. An inlet system for liquid dispensers comprising an inlet port for receiving liquid from an attached portable supply container, means projecting upwardly from said port for opening a wall of a supply container during attachment thereof to the dispenser, venting means projecting upwardly from said port for admitting pressure through the opening into an attached container, and means operative to move said venting means through said opening and into the container during attachment of the container to the dispenser.
22. An inlet system for liquid dispensers comprising an inlet port for receiving liquid from an

5 attached portable supply container, piercing and cutting means including at least one piercing point and a tubular shank extending axially from said port for opening a frangible wall of the
5 container during attachment thereof to the dispenser, and venting means for admitting pressure into the attached container, said venting means including a tube section located inside of said tubular shank, and means mounting said tube
10 section for movement in response to movement of the container wall prior to the formation of the opening in said wall.

23. An inlet system for liquid dispensers comprising an inlet port for receiving liquid from an attached supply container, piercing and cutting means including at least one piercing point and a tubular shank extending axially from said port for opening a frangible wall of a supply container during attachment thereof to the dispenser and venting means for admitting pressure into an attached container, said venting means including a fixed tube section, a movable

tube section telescopically connected with said fixed section and yieldable means normally holding said movable tube section in an extended position inside of said tubular shank while permitting movement thereof toward said port during attachment of a container to the system.

24. A supply container for liquid lubricant dispensers and the like having a bottom wall comprising a centrally disposed frangible wall section and means between the margins of said wall and said central section for draining liquid into said central section in a plurality of separate streams.

25. A supply container for liquid lubricant dispensers and the like having a frangible sheet metal bottom wall and a plurality of symmetrically spaced keying elements inside the margins of said wall and projecting from the plane thereof for cooperation with complementary keying elements of a keyed dispenser inlet system. 20
